FUSE BLOWING DEVICE FOR IGNITER
TUBESHans Klemperer, Belmont, Mass., assignor to
Raytheon Manufacturing Company, Newton,
Mass., a corporation of Delaware

Application March 25, 1941, Serial No. 385,075

13 Claims. (Cl. 315—271)

This invention relates to an arrangement for insuring the melting of the fuse wires in series with igniter elements in an igniter tube of the type which I have disclosed and claimed in my copending application, Serial No. 261,399, filed March 11, 1939, for an improvement in Electrical apparatus. In such a tube a definite minimum amount of power is necessary in order to blow the fuse upon the breakdown of the insulation of the igniter element associated therewith. In some instances the igniting impulse-supplying circuit is insufficient for maximum reliability of operation.

An object of this invention is to insure the melting of each fuse upon the breakdown of the insulation of the associated igniter element.

Another object is to provide a separate source of power for blowing the fuse.

Another object is to cause the source of fuse-blown power to operate in such a way as to provide minimum interference with the initiation of the arc spots on the cathode of the tube and with the normal operation of the tube.

A still further object is to provide simple and reliable means for accomplishing the foregoing objects.

The foregoing and other objects of this invention will be best understood from the following description of an exemplification thereof, reference being had to the accompanying drawing, wherein the figure is a circuit diagram illustrating one embodiment of my invention.

In the arrangement illustrated, 1 represents a controlled ignition type of discharge tube of the kind more fully described and claimed in my copending application above referred to. This tube consists of an envelope containing a pool type cathode 2, preferably of mercury, although other materials, such as gallium and the like, could be used. An anode 3 is adapted to cooperate with the cathode. Adjacent the cathode is a plurality of igniter elements 4. These igniter elements consist of a conductor insulated and separated from the pool cathode 2 by a layer of insulation, such as glass. The outside surface of the glass layer is in contact with the surface of the mercury pool 2. The conducting portion of each of the igniter elements 4 is connected through a fuse 5 to a common conductor 6 which constitutes the lead-in conductor for the igniter elements 4. Each of the fuses 5 is designed so as to fuse at a relatively low current of the order of 100 milliamperes. The tube 1 is adapted to be energized from a pair of terminals 7 and 8 which are to be connected to a suitable source

of alternating current. The anode 3 may be connected directly to one of the terminals 8, while the cathode 2 is connected through a suitable load device to the terminal 7.

In order to supply the igniting elements 4 with igniting impulses, an ignition transformer 10 is provided. This transformer has a secondary 11 which is connected between the igniting elements 4 and the cathode 2. The primary winding 12 of the transformer 10 is supplied with peaked igniting impulses from a peaking transformer 13, which in turn is energized through a phase-shifting device 14 from the alternating current terminals 7 and 8. The phase-shifting device 14 may be adjusted so that each voltage peak occurs at the desired portion of the alternating voltage cycle applied to the tube 1.

A fuse-blowing transformer 15 is provided for the purpose of supplying power for blowing each fuse 5 upon breakdown of the insulation on its associated igniter element 4. The transformer 15 has a primary winding 16 which is energized from the alternating current terminals 7 and 8. The secondary winding 17 of the transformer 15 is connected in series with a rectifier tube 18 between the igniting elements 4 and the cathode 2. The rectifier tube 18, which may be of the gas or vapor-filled type, is preferably provided with a thermionic cathode 19 connected in series with the secondary 17 to the igniter elements 4. The rectifier tube 18 is also provided with an anode 20 connected directly to the cathode 2.

When the system described above is energized, igniting impulses will be supplied through the members 14, 13, 12 and 11 to the igniting elements 4, and an arc spot will be initiated on the cathode 2 during each conducting half cycle applied to the tube 1 at the proper phase angle, as determined by the phase-shifting device 14. If, however, the insulation on any one of the igniter elements 4 breaks down, a considerable decrease in the resistance or impedance through the igniter circuit is created. Thereupon when the voltage on the secondary 17 is in the correct polarity, the rectifier 18 will conduct a sufficient amount of current which will pass through the fuse 5 associated with the defective igniter element 4, causing said fuse to melt and disconnect the defective igniter. Usually it is desirable to place a resistance 21 in series with the igniter elements 4 so as to limit the current supplied through the rectifier tube 18 to a value which is insufficient to establish or maintain a true arc on the cathode 2. The resistance 21, for

example, may be of such a value as to limit the current supplied through the rectifier tube 18 to the order of 100 or 200 milliamperes. Under these conditions it is relatively unimportant as to the polarity of conduction of the rectifier 18 or of the voltage on the secondary winding 17. The presence of the resistance 21 will prevent the power supplied from the secondary winding 17 from establishing or maintaining an arc spot on the cathode 2 at some undesirable point on the voltage wave supplied to the tube 1. However, it is desirable that the melting of the fuse wire 5 should occur during the inactive portion of the alternating voltage cycle applied to the tube 1, namely that half cycle in which the anode 3 is negative. For this purpose the phase of the voltage applied to the primary winding 16 is reversed, as indicated at 22, and the polarity of the rectifier 18 is so chosen that current flows through said rectifier through the defective igniter element 4 only during the inactive half cycle of the voltage wave applied to the tube 1. In addition, it is often desirable to limit the voltage applied through the secondary winding 17 so that a voltage less than that required to create and support an arc spot on the cathode 2 is impressed between the conductor 6 and said cathode. For example, if the voltage drop through the tube 18 is of the order of 10 volts, the voltage on the secondary winding 17 may have a peak value of about 15 volts, leaving only five volts to be impressed between the conductor 6 and the cathode 2, which while sufficient to blow each fuse 5, when necessary is insufficient to create and support an arc spot on the cathode 2.

The system which I have described above insures that upon breakdown of any one of the igniter elements 4, said igniter element will be disconnected from the system within the next half cycle so that the tube 1 is conditioned to start normal operation during the next normal conducting half cycle of the voltage wave supplied thereto.

Of course it is to be understood that this invention is not limited to the particular details as described above as many equivalents will suggest themselves to those skilled in the art. For example, other arrangements for supplying igniting impulses to the igniter elements 4 could be devised, and also the tube 1 could be connected in any type of system in which periodic ignition is desired. It is accordingly desired that the appended claims be given a broad interpretation commensurate with the scope of the invention within this art.

What is claimed is:

1. In combination, an element opposing flow of current, means in series with a fusible member for impressing a first-voltage across said element, which voltage during operation may attain a value sufficient to produce breakdown and flow of current through said element; said means having sufficiently high impedance to limit the current flow upon said breakdown to a value insufficient to fuse said fusible member, and separate means in series with said fusible member for impressing a second voltage across said element, said second voltage being insufficient to cause breakdown of said element, said separate means having sufficiently low impedance to pass a sufficient current through said fusible member to fuse said member upon breakdown of said element.

2. In combination, an insulating element opposing flow of current, means in series with a

75 fusible member for impressing a first-voltage across said element, which voltage during operation may attain a value sufficient to produce breakdown and flow of current through said element, said means having sufficiently high impedance to limit the current flow upon said breakdown to a value insufficient to fuse said fusible member, and separate means in series with said fusible member for impressing a second voltage across said element, said second voltage being insufficient to cause breakdown of said element, said separate means having sufficiently low impedance to pass a sufficient current through said fusible member to fuse said member upon breakdown of said element.

20 3. In combination, a discharge tube comprising an arc type cathode, an anode, and an igniter element for initiating an arc spot on said cathode, means in series with a fusible member for impressing an igniting voltage between said igniter element and said cathode, and separate means for passing sufficient current through said fusible member to fuse said member upon breakdown of said igniter element.

25 4. In combination, a discharge tube comprising an arc type cathode, an anode, and an igniter element comprising a conductor insulated and separated from said cathode by an insulating layer for initiating an arc spot on said cathode, means in series with a fusible member for impressing an igniting voltage between said igniter element and said cathode, and separate means for passing sufficient current through said fusible member to fuse said member upon breakdown of said insulating layer.

30 5. In combination, a discharge tube comprising a plurality of igniter elements for initiating an arc spot on said cathode, a fusible member in series with each of said igniter elements, means for impressing an igniting voltage between each of said igniter elements and said cathode through the associated fusible member, and separate means for passing sufficient current through each fusible member to fuse said member upon breakdown of its associated element.

35 6. In combination, a discharge tube comprising a plurality of igniter elements each comprising a conductor insulated and separated from said cathode by an insulating layer for initiating an arc spot on said cathode, a fusible member in series with each of said igniter elements, means for impressing an igniting voltage between each of said igniter elements and said cathode through the associated fusible member, and separate means for passing sufficient current through each fusible member to fuse said member upon breakdown of its associated insulating layer.

40 7. In combination, a rectifying discharge tube comprising an arc type cathode, an anode, and an igniter element for initiating an arc spot on said cathode, means for impressing an alternating voltage between said cathode and anode, means in series with a fusible member for impressing an igniting voltage between said igniter element and said cathode during the normally-conductive half cycle of said alternating voltage, and means for impressing another voltage source between said igniter element and said cathode in series with said fusible member during the normally non-conductive half cycle of said alternating voltage, said voltage source being adapted to pass sufficient current through said fusible member to fuse said member upon breakdown of said igniter element.

45 8. In combination, a rectifying discharge tube

comprising an arc type cathode, an anode, and an igniter element comprising a conductor insulated and separated from said cathode by an insulating layer for initiating an arc spot on said cathode, means for impressing an alternating voltage between said cathode and anode, means in series with a fusible member for impressing and igniting voltage between said igniter element and said cathode during the normally-conductive half cycle of said alternating voltage, and means for impressing another voltage source between said igniter element and said cathode in series with said fusible member during the normally non-conductive half cycle of said alternating voltage, said voltage source being adapted to pass sufficient current through said fusible member to fuse said member upon breakdown of said insulating layer.

9. In combination, a discharge tube comprising an arc type cathode, an anode, and an igniter element for initiating an arc spot on said cathode, means in series with a fusible member for impressing an igniting voltage between said igniter element and said cathode, and a rectifier connected in series with a source of alternating voltage connected between said igniter element and said cathode in series with said fusible member, said rectifier and source being adapted to pass sufficient current through said fusible member to fuse said member upon breakdown of said igniter element.

10. In combination, a discharge tube comprising an arc type cathode, an anode, and an igniter element comprising a conductor insulated and separated from said cathode by an insulating layer for initiating an arc spot on said cathode, means in series with a fusible member for impressing an igniting voltage between said igniter element and said cathode, and a rectifier connected in series with a source of alternating voltage connected between said igniter element and said cathode in series with said fusible member, said rectifier and source being adapted to pass sufficient current through said fusible member to fuse said member upon breakdown of said insulating layer.

11. In combination, a rectifying discharge tube comprising an arc type cathode, an anode, and

an igniter element for initiating an arc spot on said cathode, means in series with a fusible member for impressing an igniting voltage between said igniter element and said cathode during the normally-conductive half cycle of said alternating voltage, and a rectifier connected in series with a source of alternating voltage connected between said igniter element and said cathode in series with said fusible member, said rectifier and source being adapted to pass sufficient current through said fusible member to fuse said member upon breakdown of said igniter element, said rectifier being of a polarity to supply current to said igniter element during the normally non-conductive period of said discharge tube.

12. In combination, a discharge tube comprising an arc type cathode, an anode, a plurality of igniter elements for initiating an arc spot on said cathode, a fusible member in series with each of said igniter elements, means for impressing an igniting voltage between each of said igniter elements and said cathode through the associated fusible member, and a rectifier connected in series with a source of alternating voltage connected between said igniter elements and said cathode in series with said fusible members, said rectifier and source being adapted to pass sufficient current through each of said fusible members to fuse said member upon breakdown of its associated igniter element.

13. In combination, a discharge tube comprising an arc type cathode, an anode, and a plurality of igniter elements each comprising a conductor insulated and separated from said cathode by an insulating layer for initiating an arc spot on said cathode, a fusible member in series with each of said igniter elements, means for impressing an igniting voltage between each of said igniter elements and said cathode through the associated fusible member, and a rectifier connected in series with a source of alternating voltage connected between said igniter element and said cathode in series with said fusible member, said rectifier and source being adapted to pass sufficient current through each of said fusible members to fuse said member upon breakdown of its associated insulating layer.
